ARTICLE OF APPAREL

Klee Oppenheimer, New York, N. Y.

Application February 27, 1945, Serial No. 579,921

5 Claims. (Cl. 2—253)

1

This invention relates to articles of apparel or garments of outer wear for men, women and children, such as trousers, knickerbockers, riding or work breeches or skirts, and more particularly to a novel construction of pockets, including auxiliary pockets for a pen and pencil set or similar set of utensils, constructed and arranged in conjunction with the larger pockets of the garment to have the contents of such auxiliary pockets positioned for ready access and yet be unobtrusively contained in such pockets without interference with the ordinary and conventional entry into and egress from the main pocket sections.

The construction of the present invention is an improvement upon a garment pocket construction disclosed and described in my issued Patents Nos. 2,236,694 dated April 1, 1941, and 2,262,402 dated November 11, 1941. In such patents, I describe a pocket structure for an article of apparel comprising two completely separate and individually accessible compartments fabricated from a single piece of material, the duplex compartment pocket being secured to the body of the garment along the conventional seam or seams of the garment in substantially the conventional position of the usual pockets provided with garments of this type. The two-compartment pocket as disclosed in the aforesaid patents is adapted to be retained in proper position for ready access to the contents of either compartment by the hands of the user through a single opening in the garment.

The present invention has for its object the provision of such duplex construction incorporating therein a pair of auxiliary vertically disposed pockets for, for instance, a pen and pencil set, which auxiliary pockets are so constructed and arranged with respect to the duplex pocket construction and the opening thereto as to permit ready access to the contents of either compartment and not to interfere with the conventional manner of utilizing such duplex pocket construction, and yet provide ready accessibility to such auxiliary pockets to insert the pen or pencil or other utensil or object into such auxiliary pockets and to remove the same therefrom whenever required.

The present invention consists in more than the mere provision of a pair of auxiliary pockets in the aforesaid duplex pocket construction, as the provision of such auxiliary pockets necessitates certain changes in the construction of the duplex pocket arrangement of the aforesaid patents to provide the ready accessibility of such auxiliary pockets and their disposal in the opening to the duplex pocket construction, which

2

makes the entire arrangement one of extreme utility, while at the same time providing a neat appearance of the garment section in which the structure has been incorporated.

5 A particular embodiment of my invention is illustrated in the accompanying drawing, in which Fig. 1 is an outside view of the upper portion of a pair of trousers in the construction of which my improvement has been embodied; 10 Fig. 2 is an inside view of the waist region of a pair of trousers showing the application thereto of my novel duplex pocket arrangement and auxiliary pockets; Fig. 3 is a view similar to Fig. 1 with part of the material of the trousers broken away to illustrate the structure of the pocket arrangement; Fig. 4 is a section on the line 4—4, on a somewhat enlarged scale, of Fig. 1; Fig. 5 is a section similar to Fig. 4, but showing the pocket construction collapsed, i. e. without the pen and pencil set included in the auxiliary pockets; and 20 Fig. 6 is a section on the line 6—6 of Fig. 1.

Referring more particularly to the drawings, in which similar reference characters identify similar parts in the several views, 10 represents 25 a portion of a trouser leg having the conventional side seam 11 joining the fabric strips constituting the leg, and a waist band 12. Immediately in line with the side seam 11 and below the waist band 12 there is formed a substantially V-shaped 30 opening 13, the two sides 14 and 15 of which are disposed at an angle to the trouser seam 11, thereby forming an opening for the duplex pocket construction, which opening diverges upwardly until the sides of the opening meet the waist band 12.

The pocket structure is preferably constituted 35 of a single piece of any suitable material conventionally utilized in fabricating a garment pocket, such single strip of material being cut 40 from a pattern which is then doubled over upon itself along the line 16 and seamed at the opposite edges 17 throughout the length of the pocket and also along the two bottom edges 18 and 19 of the two compartments 20 and 21 to be formed, 45 and along the curved cut-out 22 extending substantially along the center of the single strip of fabric from the bottom edge thereof to a little below the vertical mid-point thereof.

The two-compartment pocket, as thus constituted, is secured as a whole to the waist band 12. A strip of facing material 23, preferably of the same material as the garment, is stitched to the inner wall of the pocket to constitute a facing for the entire V-shaped opening 13, and extends 55 sideways from each edge thereof to the extent

indicated by the dotted lines in Figs. 1 and 2, and in full lines in Fig. 3, in which the trouser material has been cut away to show the outline of such facing material 23.

The facing material 23 is backed by the trouser pocket fabric strip 24 and is constructed to provide between such facing 23 and the pocket fabric 24 a pair of auxiliary pockets 25 and 26 into which may be inserted a pen and pencil set 27 and 28 by means of their clips 29 and 30. The upper portions of the auxiliary pockets 25 and 26 are backed by a rectangularly shaped reinforcing strip 31 which is attached at the top thereof to the looped lower edge of the facing 23 extending from the waist band to the auxiliary pocket by stitching 32 and to the pocket fabric backing by stitching 33. Bar tacks 34, 35 and 36 separate the individual auxiliary pockets 25 and 26. The auxiliary pockets 25 and 26 are formed by the stitching 37 and such pockets at their top are backed by a strip of material 38 which is preferably of the same material as the garment and the facing strip 23. At the lower end of the facing strip 23, constituting the front of the auxiliary pocket construction, such facing strip is turned upwardly and stitched to the back of the pocket material.

It will be noted that my novel construction of duplex pocket provides a pair of auxiliary pockets readily accessible in the opening 13 of the duplex pocket construction, for insertion thereinto or removal therefrom, of any elongated objects, for instance, those constituting a pen and pencil set, although, of course, in a work or utility garment the pockets may be utilized to hold tools or utensils, for instance, a screwdriver or a spark-plug tester, a tool of an automobile mechanic conventionally made in the form of an elongated body with or without a clip of the type used with a pen or pencil.

The provision of the auxiliary pockets in the precise position, and their configuration as hereinabove described and illustrated in the drawings, has been found to be of extreme utility and ready availability and greatly enhances the value of the duplex pocket construction described and illustrated in my prior patents.

While I have described a specific embodiment of my invention, it will be obvious that various changes in the specific arrangement described, particularly in the sewing and securement together of the various parts and the construction and configuration of the pockets, may be made without departing from my invention.

I claim:

1. In a garment for outer wear, a duplex pocket construction comprising in combination with the garment having an opening, a single strip of fabric folded into two superposed panels and stitched to the garment along its upper edge and having an opening substantially corresponding to that in the garment material, said opening having a facing of the same material as that of which the garment is made, and an auxiliary pocket structure comprising a pocket wholly disposed within the

65

opening of the garment giving access to the duplex pocket construction, said auxiliary pocket having the same facing material as the facing for the duplex pocket construction.

2. In a garment for outer wear, a duplex pocket construction comprising in combination with the garment having an opening, a single strip of fabric folded into two superposed panels and stitched to the garment along its upper edge and having an opening substantially corresponding to that in the garment material, a facing for said opening of the same material as the garment, and an auxiliary pocket structure wholly disposed within the opening of the garment giving access to the duplex pocket construction, and being formed in the facing material of the duplex pocket construction.

3. In a garment for outer wear, a duplex pocket construction comprising in combination with the garment having an opening, a single strip of fabric folded into two superposed panels and stitched to the garment along its upper edge and having an opening substantially corresponding to that in the garment material, said opening having a facing of the same material as that of which the garment is made, and an auxiliary pocket structure comprising a plurality of pockets wholly disposed within the opening of the garment giving access to the duplex pocket construction, said auxiliary pockets having the same facing material as the facing for the duplex pocket construction.

4. An outer garment of the class described having a substantially V-shaped side opening, the edges of which diverge upwardly toward the waist band of the garment and from the side seam of the garment, and a pocket structure comprising two superposed panels of fabric assembled within said garment, said pocket structure having two compartments both readily accessible through the garment opening, one compartment being disposed forward of said opening and the other compartment to the rear thereof, and an auxiliary pocket formed with said duplex pocket construction and disposed substantially wholly within the outlines of said V-shaped garment opening for containing therein an elongated object readily accessible through said V-shaped garment opening.

5. An outer garment as claimed in claim 4 having a reinforcing strip of substantially rectangular configuration disposed rearwardly of the upper portion of the auxiliary pocket.
